CLAIM

The ornamental design for a rear bumper for an automobile, as shown and described.

DESCRIPTION

FIG. 1 is a front elevational view of a rear bumper for an automobile in accordance with our new design; FIG. 2 is a top plan view of the rear bumper in accordance with our new design of FIG. 1; FIG. 3 is a bottom plan view of the rear bumper in accordance with our new design of FIGS. 1 to 2; FIG. 4 is a right side elevational view of the rear bumper in accordance with our new design of FIGS. 1 to 3; FIG. 5 is a left side elevational view of the rear bumper in accordance with our new design of FIGS. 1 to 4; FIG. 6 is a front, right and top side perspective view of the rear bumper in accordance with our new design of FIGS. 1 to 5; and, FIG. 7 is a front, left and bottom side perspective view of the rear bumper in accordance with our new design of FIGS. 1 to 6.

The inside surfaces of the rear bumper shown in FIGS. 2, 6 and 7 in broken lines form no part of the claimed design.
